W. SPECHT

CLAMP

Filed July 26, 1921

Inventor:
Woldemar Specht,
by *Albert S. Davis*
His Attorney

UNITED STATES PATENT OFFICE.

WOLDEMAR SPECHT, OF SCOTIA, NEW YORK, ASSIGNOR TO GENERAL ELECTRIC COMPANY, A CORPORATION OF NEW YORK.

CLAMP.

Application filed July 26, 1921. Serial No. 487,812.

To all whom it may concern:

Be it known that I, WOLDEMAR SPECHT, a citizen of the United States, residing at Scotia, in the county of Schenectady, State 5 of New York, have invented certain new and useful Improvements in Clamps, of which the following is a specification.

My invention relates to improvements in clamps adapted for use in securing two 10 substantially flat members in a position of relative perpendicularity and an object of my invention is to provide a clamp which is economical in construction and simple and flexible in application, and more particularly an object of my invention is to 15 provide a clamp for securing barrier plates to the bases of electric switches and the like without limiting the barrier plate to a particular position on the switch bases or 20 requiring a barrier plate of heavier construction than is necessary to fulfill its function, that is, to prevent passing of the arc.

Heretofore, barrier plates have been secured to the switch bases by drilling holes 25 in the bases and in the barrier plates edge-wise, the holes in the barrier plates being leaded and tapped to receive cap screws or studs projecting through the counter-sunk holes in the switch bases. This method 30 is expensive particularly when the switch bases and barriers are of slate, marble or like brittle material as the drilling costs are high and breakage heavy and furthermore since the barrier has to be drilled edge- 35 wise, it is necessary to have the barrier needlessly thick for the function it has to fulfill, in order to have sufficient thickness of material for the size of the holes required and the requisite strength for such 40 heavy materials after the holes have been drilled. With such construction the position of the barrier is definitely fixed once the holes are drilled in the switch base and any desired change in the position of the barrier practically necessitates drilling another switch base.

According to my invention, I provide a barrier support which eliminates drilling holes in the switch base and the edge-wise 45 holes in the barrier plate, it being neces-

sary to have a smaller number of holes in the barrier plate and these holes are drilled not edgewise but transversely through the smallest dimension of the barrier plate. It is therefore possible to use 55 a much lighter, that is thinner, barrier plate as by my invention I am able to use the static strength of the materials such as slate, marble, and the like to the greatest advantage.

My invention will be better understood from the following description taken in connection with the accompanying sheet of drawings, and its scope will be pointed out 60 in the appended claims.

Fig. 1 is a side elevation, parts being broken away, illustrating an embodiment of my invention; Fig. 2 is an end elevation of the embodiment of my invention shown in Fig. 1; Fig. 3 is a side elevation of 70 a modification of my invention, and Fig. 4 is a sectional view on the line IV—IV of Fig. 3.

In the embodiment of my invention shown in Figs. 1 and 2, two substantially 75 flat members 1 and 2, such as a switch base and its barrier plate, respectively, are shown secured to each other at right angles by my improved clamping device, the flat members being shown partly broken 80 away, as the length thereof is immaterial as far as my invention is concerned. This clamping device comprises a U-shaped or substantially rectangular channel shaped member 3 having the legs or parallel 85 flanges thereof provided at one end with extensions 4 arranged to embrace or grasp the flat member 2 and to be securely fastened thereto by a bolt 5 extending through a hole in the member 2 and registering 90 holes in the extensions 4. Cooperating with the U-shaped member 3 is an L-shaped member 6 having one leg 7 thereof longitudinally movable or adjustably positioned within the channel of the U-shaped 95 member 3. The other leg 8 of the L-shaped member 6 projects from the leg 7 in the direction of the extensions 4 and is adapted to project across the outer face of the flat member 1 so as to abut this member. The 100

position of the L-shaped member 6 relative to the U-shaped member 3, that is to say the distance between the leg 8 and the bolt 5, may be varied by any suitable adjusting means such as a nut 9 on a threaded extension 10 of the L-shaped member 6, the nut 9 bearing against a suitable washer 11 which in turn bears against the flanges and web of the U-shaped or channel member 3. The L-shaped member 6 is preferably of rectangular cross-section to register with the opening in the U-shaped member 3 and thereby prevent any turning or rotation of the L-shaped member 6 when turning the nut 9 thereon. Consequently turning the nut 9 in a direction to draw the leg 8 of the L-shaped member 6 towards the bolt 5 will cause the leg 8 to draw the flat members 1 and 2 together, the edge of flat member 2 abutting against the inner face of the member 1. The flat members 1 and 2 are thereby securely clamped in a position of relative perpendicularity. Obviously, with the arrangement shown the flat member 2 may be clamped to the flat member 1 at right angles thereto, in any number of positions, as there are no bolt holes or the like in the two members that have to be brought into register before the members can be secured together. Furthermore, with only two transverse bolt holes, one for each bolt 5 in the flat member 2, the cross-section on the line of the bolt holes is not materially reduced and substantially the full static strength of the material is available so that in the case of the flat member 2 being of relatively frangible material, such as slate, marble and the like, it need be no thicker than necessary to fulfill the function for which it is intended.

In the modification of my invention shown in Figs. 3 and 4, the web 12 of the channel or U-shaped member 3 instead of being substantially flat and perpendicular to the flanges or legs, as is the case in Figs. 1 and 2, is curved. In this case in order to prevent undue binding of the L-shaped member 6 of rectangular section in the U-shaped member 3, the latter is provided with a lip 13 to hold the L-shaped member 6 in alignment away from the narrower or curved portion of the U-shaped member 3.

What I claim as new and desire to secure by Letters Patent of the United States, is:—

1. In a clamping device of the class described, a channel shaped member provided at one end with extensions to the flanges thereof, in the planes of the flanges whereby said channel member may be secured to an article to be clamped, a member positioned within said channel member longitudinally movable therein and provided

with a projecting portion substantially parallel to the extensions of said channel member and adapted to abut another article to be clamped, and means carried on said movable member adapted to draw said projecting portion and said extensions toward each other to hold the articles to be clamped. 70

2. A clamping device adapted to secure two substantially flat members in a position of relative perpendicularity, comprising a U-shaped member, projecting portions forming extensions to the legs of said U-shaped member whereby the U-shaped member is adapted to be secured to one of said flat members, an L-shaped member having one leg movable within said U-shaped member and the other leg extending therefrom in the direction of the legs of the U-shaped member whereby the L-shaped member is adapted to abut against the outer face of the other of said flat members, and means for varying the position of the movable leg of said L-shaped member longitudinally in said U-shaped member. 80

3. In a clamping device of the class described, a U-shaped member provided at one end with extensions to the legs thereof, an L-shaped member having the longer leg thereof movable within said U-shaped member and the shorter leg substantially parallel to the legs of said U-shaped member, means on the end of said U-shaped member adjacent said shorter leg of the L-shaped member for guiding the longer leg of said L-shaped member to prevent the same from binding in the web of the U-shaped member, and means carried on the longer leg of said L-shaped member adapted to draw said shorter leg and said extensions toward each other to hold articles to be clamped. 95

4. The combination with two substantially flat members, of means for securing one of said members to the other at right angles thereto, comprising two U-shaped members, one at each end of one of said flat members, said U-shaped members being provided with parallel projecting portions adapted to be secured to said flat member and said U-shaped members extending partially across the edges of the other of said flat members, and an L-shaped member arranged in each of said U-shaped members having one leg adjustably positioned therein and the other leg extending over the outer face of the other of said flat members, and means for longitudinally adjusting the position of said L-shaped members in said U-shaped members to clamp said flat members together. 110

5. The combination with two substantially flat members, of means for securing one of said members to the other at right angles thereto, comprising a U-shaped member provided with substantially parallel 120

projecting portions embracing and secured to one of said flat members and an L-shaped member having one leg adjustably positioned in said U-shaped member and the other leg projecting over the outer face of the other flat member, and means for longitudinally adjusting the position of said

L-shaped member in said U-shaped member to draw said flat members together and maintain them in a position at right angles to each other.

In witness whereof, I have hereunto set my hand this 25th day of July, 1921.

WOLDEMAR SPECHT.
